PAPER MAKING MACHINE

Filed Aug. 12, 1926

2 Sheets-Sheet 2

UNITED STATES PATENT OFFICE

CHARLES B. BRIEDE AND HERMAN L. KUTTER, OF HAMILTON, OHIO

PAPER-MAKING MACHINE

Application filed August 12, 1926. Serial No. 128,810.

This invention relates to paper-making machinery of the type adapted for the formation of a web or continuous sheet of paper from paper stock, and more particularly to 5 that type of paper-making machinery in which an endless paper-making part, such for example as a wire or a belt, is employed in carrying the paper or paper stock.

One of the principal objects of the invention is to provide means for stringing the endless paper-making part or wire.

Another object is to provide means for moving one of the paper-making elements, and particularly the suction roll element, out 15 of normal position to facilitate replacement of the endless paper-making part or wire.

Other and further objects of the invention will appear from the following description taken in connection with the accompanying 20 drawing, in which:

Fig. 1 is a front elevation of a paper-making machine of the Fourdrinier type embodying the present invention;

Figs. 2 and 3 are enlarged front elevations 25 of the inlet and the delivery end of the machine shown in Fig. 1;

Fig. 4 is a vertical end view of the delivery or couch roll end of the machine shown in Figs. 1 and 3, the parts being in normal 30 operating position; and

Fig. 5 is a view similar to Fig. 4 showing the couch roll moved forwardly out of its normal operating position.

Referring particularly to Figs. 1, 2 and 3, 35 these figures show the present invention installed in connection with a paper-making machine of the Fourdrinier type, that is, a machine having a wire 20 which is adapted to receive paper stock from a flow box 21, which latter may be of usual and well-known construction. In machines of the type illustrated the wire or screen, which is endless, passes over a breast roll 22 at the inlet end 40 of the machine and over a couch roll 23 at the delivery end of the machine. In passing from the breast roll element 22 to the couch roll element 23 the wire passes successively over the table roll element 24 and the suction box element 25, these latter paper-making 45 elements being preferably so constructed

and arranged that they may be withdrawn frontwise out of the line of the web of paper in order to permit removal or replacement of the wire. The elements 24 and 25 have supporting carriages 32 extending to the ground 55 and movable thereon so that these elements may be rolled frontwise out of the line of the wire, but the specific construction of the elements 24 and 25 and of the particular form of supporting means illustrated constitute no part of the present invention and are therefore not described or illustrated in detail. Suffice it to say that when it is desired to remove the table roll element 24 for the replacement of the wire 20, the breast roll element 22 is first removed from its normal position and suspended from the element 24 by suitable means (not shown) in the position indicated by dotted lines at 30, so that the breast roll element is carried forwardly 60 with the table roll element 24, and likewise the guide or tension roll 31 may be suspended in like manner from the opposite end of the table roll element 24 so as to be removed therewith.

Novel means is herein disclosed for moving a paper-making element frontwise out of the line of the endless paper-making part, such means being illustrated in connection with the couch roll element 23 of the machine, although it should be understood that the invention is not limited in its application to a couch roll element but is applicable to the other elements of the paper-making machine. Referring particularly to Figs. 3, 4 and 5, the paper-making element or couch roll 23 has a movable part or couch roll proper 35 over which the wire passes during normal operation of the machine, as is well understood. The movable part or roll 35 is mounted for rotation in suitable bearings carried by front and rear carriages 36 and 37 respectively which are so constructed and mounted as to permit the roll 35 to be moved forwardly 70 from its normal operating position shown in Fig. 4 to the position shown in Fig. 5, or vice versa. The front carriage may be provided with anti-friction rollers 38 adapted to roll upon a suitable track means 39 laid on the ground or in the foundation of the machine.

65

Owing to the weight of the parts it may be desirable to provide means for positively moving the carriage 36 over its track and for this purpose the track 39 is provided with gear teeth 40 adapted to engage with corresponding gear teeth 41 formed on one of the rollers 38, and such roller 38 may be actuated by any suitable means such as the operating handle 42 which, as herein shown, has a driving connection with the gear teeth 41 of the roller 38.

The rear carriage 38 is provided with a suspension arm or bracket 45 having a roller bearing 46 adapted to roll upon an elevated track 47, which track is normally supported at its opposite ends upon front and rear supports or pedestals 48 and 49 respectively, which supports have upwardly extending arms 50 connected by a bracing and supporting member 51 which serves as an attachment or support for one end of the wire-stringing means which will be hereinafter more fully described. The front support 48 is provided with an opening 52 of such size as to pass the movable roll 35 and the front carriage 36 when these parts are rolled forwardly as shown in Fig. 5. The rear pedestal or support 49 is provided with a plurality of supporting and guiding rolls 54 normally supporting the rear end of the track 47, but so constructed and arranged as to carry the entire weight of the track 47 when the latter is withdrawn to the rear as illustrated for example in Fig. 5. The lower rolls 54 are preferably connected with a crank or other suitable actuating device 55 by which these lower rollers may be rotated in unison to move the track 47 back and forth as desired. The forward end of the track 47 is normally supported by a suitable ledge or shoulder 56 formed in the front support 48.

During normal operation of the paper-making machine the couch roll and associated parts are in the position illustrated in Fig. 4, it being understood that the wire 20 passes between the roll 35 and track 47 on its upper side and between the roll 35 and the floor or foundation on the lower side. The couch roll is locked in position by means of bolts 57 or other suitable securing means, and it will be noted that the lower part of the rear carriage is inclined and cooperates with the inclined or wedge-shaped supporting means 58 which latter may be of such height as to raise the roll 46 from the track 47 and to take the weight of the couch roll 35 and of the rear carriage as these parts are moved home to their normal operating position.

Wire-stringing means is provided to facilitate the stringing of the new wire and such means, in the form herein illustrated, comprises an overhead track means which may consist of two spaced apart supporting cables 70 secured at the rear end of the machine 65 upon the bracing and supporting member 51,

which supporting cables extend forwardly lengthwise of the paper-making machine, passing over the supporting pulleys 72 and being secured to the foundation in any suitable manner as at 73. A carriage 74 is mounted upon each supporting cable and is adapted to be drawn along the supporting cable, suitable means for drawing the carriage being provided in the form of a traction cable 75 which may pass forwardly over pulley 71 to a suitable operating device or reel 76, the construction of which is such that the carriage means 74 may be drawn forwardly slowly from its position at the delivery end of the machine as shown in Fig. 3, to the inlet end of the machine as shown in Fig. 1.

The carriages 74 are each provided with a roll-supporting or bearing member 77 pivotally connected with the carriage at 78 and normally supported in the position shown in Fig. 3 by means of a latching device 79. The roll-supporting members 77 are constructed in the form of hooks so that when unlatched at 79 the roll-supporting members may swing downwardly about the pivot pins 78 into such position that the roll may be readily placed in the supporting member 77. The roll-supporting members 77 form bearings for roll caps 80 which, as best shown in Fig. 4, are provided with stub shafts 81 extending therefrom. The new wire screen or wire is commonly rolled upon a roll 82, and when it is desired to support the roll in the carriage preparatory to stringing the new wire, the caps 80 are placed over the ends of the roll 82 and clamped thereon by any suitable means such as set screws 83. The roll of wire with the caps 80 secured thereon is then placed in the roll-supporting members 77 and the latter are swung upwardly and latched in position as indicated in Fig. 3.

Slidably mounted on the supporting cables 70 between the carriages 74 and the upwardly extending arms 50 of the couch roll frame are a number of suspenders 85 each of which 110 comprises a stringer tube 86 supported at opposite ends by suspender rods or cables 87 as best shown in Fig. 3. Extending rearwardly from the bracing and supporting member 51 are suspender arms 90 upon which 115 is mounted a suspender 91 comprising, as in the case of the suspenders 85, a stringer tube 92 and suspender rods 93.

The operation of the present invention is as follows: Assuming that the parts of the paper-making machine are in their normal operating position as illustrated in Figs. 1 and 4, and it being desired to replace the wire, the breast roll 22 and the guide or tension roll 31 may be removed from their normal positions and suspended from the tube roll frame 24, as already described. The tube roll element or frame 24 and the suction-box frame or element 25 may then be rolled 125

forwardly out of the normal line of movement of the paper and of the wire.

The suction or couch roll element 35 may be moved forwardly out of the line of the paper by first removing the locking bolts 57 and then rolling the movable suction roll part forwardly to the position indicated in Fig. 5, the movement of the suction roll being effected by operation of the operating lever 42. After the suction roll is thus moved forwardly the elevated track 47 may be moved rearwardly upon the rear pedestal or support 49 to the position indicated in Fig. 5.

The several elements of the paper-making machine being thus moved forwardly, and the old wire having been removed in any desired manner, the machine is ready for the insertion of the new wire. The roll of new wire is suspended in the carriages 74 (hereinafter referred to cumulatively as a carriage) and the free end thereof is looped and supported by the suspender 91 to form a loop of such size as to receive the suction roll element. The latter is then moved rearwardly into the loop and the suspender rod 92 removed so as to permit the wire to fall into position about the suction roll. The operating device 76 is then operated to draw the carriage forwardly towards the inlet end of the machine as indicated in Fig. 1, during which forward movement of the carriage the wire unrolls from its roll and is strung along the length of the machine. During the unwinding or stringing process the suspenders 85 are distributed along the length of the machine somewhat as indicated in Fig. 1 so as to support the upper part of the loop or wire at a height sufficient to permit the tube roll and the suction roll elements 24 and 25 to be rolled back into normal position without striking or damaging the new wire. The suspenders 85 are then disconnected from the wire to permit the latter to take its proper place upon the tube roll and suction roll elements, and the breast roll 22 and the tension roll 31 return to their normal operating positions.

A return cable 95 may be connected to the carriage 74 to facilitate the return of the latter to the starting position shown in Fig. 3. In the event that undue pressure or resistance is encountered in returning the suction roll to its operating position with the rear end resting on the support 58 recourse may be had to a jack screw (not shown) or other device to assist the operator in positioning the suction roll element.

Another method of operating the stringing means is to support the wire cloth carriage at the position occupied by the stringer roll 92, and to then carry the wire forwardly towards the breast roll by one or more of the suspenders 85, the wire cloth carriage remaining in position and unwinding to supply the wire as required. According to this method of operation the means 75 for drawing the car-

riage along the cable may be affixed to the moving suspender or may be dispensed with.

From the foregoing it will be apparent that the present invention provides means for quickly renewing or replacing the endless paper-making part or wire of a paper-making machine. Novel means is disclosed for effecting the rapid movement of the suction roll and other paper-making elements out of the path of the endless wire and for thereafter quickly returning such parts to their normal position, and likewise it provides novel means for rapidly stringing the wire without danger of injury or damage thereto.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a paper-making machine of the character described, a couch roll adapted to be moved frontwise out of normal operating position, said roll having a front carriage and track means therefor, a rear carriage and overhead track means for said rear carriage. 90
2. In a paper-making machine of the character described, a couch roll adapted to be moved frontwise out of normal operating position, said roll having a front carriage and track means therefor, a rear carriage having a suspension means, and an overhead track 95 in engagement with said suspension means. 100
3. In a paper-making machine of the character described, a couch roll adapted to be moved frontwise out of normal operating position, said roll having a front carriage supported upon and movable over the ground, a rear carriage and overhead track means for said rear carriage. 105
4. A removable couch roll comprising a revolvable member, a front carriage support for the front end of said member, a rear carriage support for the rear end of said member, said rear carriage having means for cooperating slidably with a track means, and track means for supporting said rear carriage during movement of the couch roll. 115

5. In a paper-making machine of the character described, a couch roll, a wire normally in a lane extending lengthwise of the machine and in operative engagement with 120 said couch roll, a support for said couch roll, and means for moving said couch roll to the front side of the machine out of the lane of said wire.

6. In a paper-making machine of the character described, a paper-forming element adapted to be moved frontwise out of normal operating position, said element comprising a forwardly and rearwardly movable part including front and rear carriages, a stationary 125

130

front support having an opening of such size that said movable part may pass therethrough during forward removal thereof, and track means for supporting said rear carriage during movement thereof.

7. In a paper-making machine of the character described, a paper-forming element adapted to be moved frontwise out of normal operating position, said element comprising a forwardly and rearwardly movable part including front and rear carriages, a stationary front support having an opening of such size that said movable part may pass therethrough during forward removal thereof, and overhead track means for supporting said rear carriage during movement thereof.

8. In a paper-making machine of the character described, a paper-forming element adapted to be moved frontwise out of normal operating position, said element comprising a forwardly and rearwardly movable part including front and rear carriages, a stationary front support having an opening of such size that said movable part may pass therethrough during forward removal thereof, track means for supporting said rear carriage during movement thereof, said track means being removable while the rear carriage is in its front position, and means at said front position support for supporting the rear carriage after removal of said track means.

9. Stringing means for a paper-making machine having an endless paper-making part, comprising overhead track means extending longitudinally of the paper-making machine, a carriage supported by said track means, said carriage being adapted to receive the roll of the endless paper-making part to be strung, and means for moving said carriage along said track means whereby to unroll the paper-making part and to distribute same lengthwise of the paper-making machine.

10. Stringing means for a paper-making machine having an endless paper-making part, comprising overhead track means extending longitudinally of the paper-making machine, a carriage supported by said track means, said carriage being adapted to receive the roll of the endless paper-making part to be strung, means for moving said carriage along said track means whereby to unroll the paper-making part and to distribute same lengthwise of the paper-making machine, and supporting means for supporting the upper portion of the endless paper-making part in elevated position following unrolling from the carriage.

11. Stringing means for a paper-making machine having an endless paper-making part, comprising overhead track means extending longitudinally of the paper-making machine, a carriage supported by said track means, said carriage being adapted to receive the roll of the endless paper-making

part to be strung, means for moving said carriage along said track means whereby to unroll the paper-making part and to distribute same lengthwise of the paper-making machine, and supporting means for supporting the upper portion of the endless paper-making part in elevated position following unrolling from the carriage, said supporting means comprising a plurality of suspenders adapted to be distributed along the length of the paper-making part.

12. Stringing means for a paper-making machine having an endless paper-making part, comprising overhead track means extending longitudinally of the paper-making machine, a carriage supported by said track means, said carriage being adapted to receive the roll of the endless paper-making part to be strung, means for moving said carriage along said track means whereby to unroll the paper-making part and to distribute same lengthwise of the paper-making machine, and supporting means for supporting the upper portion of the endless paper-making part in elevated position following unrolling from the carriage, said supporting means comprising a plurality of suspenders supported by said track means and adapted to be distributed along the length of the paper-making part.

13. Stringing means for a paper-making machine having an endless paper-making part, comprising track means extending longitudinally of the paper-making machine, a carriage supported by said track means, said carriage being adapted to receive the roll of the endless paper-making part to be strung, means for moving said carriage along said track means whereby to unroll the paper-making part and to distribute same lengthwise of the paper-making machine, and means associated with said carriage for preventing too-rapid unrolling of said endless paper-making part therefrom.

14. Stringing means for a paper-making machine having an endless paper-making part adapted to lie in a lane extending lengthwise of the machine, comprising means for supporting a roll of said endless paper-making part in said lane in position to be unwound and extended therein, and means for supporting said extended paper-making part in said lane including track means extending lengthwise of the machine and suspender means movable lengthwise of said track means.

15. In a paper making machine, a lower couch roll, a front carriage for supporting the front end of said roll, a rear carriage for said roll having a lower inclined face and an overhead roller, an inclined base upon which said inclined face of the rear carriage normally rests and an overhead track upon which said roller may travel during removal of said couch roll.

16. In a paper making machine, a lower couch roll adapted to be laterally removable, a carriage for rotatably supporting each end of said roll, a ground track for continuously supporting one of said carriages, a fixed base for supporting the second of said carriages in normal position and a removable overhead track for supporting said second carriage during removal. 70
- 10 17. In a paper making machine, a lower couch roll adapted to be laterally removable, a carriage for rotatably supporting each end of said roll, a ground track for continuously supporting one of said carriages, a fixed base for supporting the second of said carriages in normal position, a removable overhead track for supporting said second carriage during removal, and a fixed elevated support for said second carriage during removal of 75 said overhead track. 80
- 15 18. The combination with a removable type Fourdrinier paper machine having laterally removable table roll and suction box elements and a laterally removable couch roll, of a travelling overhead carriage for supporting wire carrying rolls and means for supporting the unrolled wire in loop form when the table roll and suction box elements and couch roll are in laterally removed position. 85
- 20 19. The combination with a removable type Fourdrinier paper machine having laterally removable table roll and suction box elements and a laterally removable couch roll, of a travelling overhead carriage for supporting wire carrying rolls and a plurality of movable suspenders for supporting the unrolled wire in loop form when the table roll and suction box elements and couch roll are in laterally removed position. 90
- 25 20. In a paper making machine of the character described, a couch roll, carriages therefor and track means associated therewith upon which said couch roll is adapted to be individually removed. 95
- 30 21. In a paper making machine of the character described, a couch roll, carriages therefor and track means associated therewith upon which said couch roll is adapted to be individually removed, said track means including an elevated track for supporting the rear end of said couch roll. 100
- 35 22. In a paper making machine of the character described, a couch roll, carriages therefor and track means associated therewith upon which said couch roll is adapted to be individually removed, said track means including an elevated rearwardly removable track for supporting the rear end of said couch roll. 105
- 40 23. In a paper making machine of the Fourdrinier type, a lower couch roll, a front carriage therefor supported upon and movable over a flooring, a rear carriage for said roll and an elevated track for said rear car- 110
- 45 115
- 50 120
- 55 125
- 60 130
- riage for supporting said couch roll in suspended position.
24. In a Fourdrinier paper machine, a lower couch roll adapted to be moved front-wise out of normal operating position, front and rear carriages for said roll, a stationary front support having an opening of such size as to permit the passage of said roll therethrough, elevated track means for supporting the rear carriage during movement thereof, said track means being rearwardly removable while the rear carriage is in its front position and means on said stationary front support for supporting the rear carriage after removal of said track means. 75
25. The combination with a removable type Fourdrinier paper machine having laterally removable table roll and suction box elements and an individually laterally removable couch roll, of a travelling overhead carriage for supporting wire carrying rolls and means for supporting the unrolled wire in loop form when the table roll and suction box elements and couch roll are in laterally removed position. 85
- In testimony whereof we hereto affix our signatures.
- CHARLES B. BRIEDE.
